UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

LOCK STRUCTURE.

Application filed August 15, 1922. Serial No. 581,968.

To all whom it may concern:

Be it known that I, JOHN B. FREYSINGER, a citizen of the United States, and a resident of Stamford, in the county of Fairfield and 5 State of Connecticut, have invented certain new and useful Improvements in Lock Structures; and I do hereby declare the following to be a full, clear, and exact description of the invention, such as will enable 10 others skilled in the art to which it appertains to make and use the same:

This invention relates to improvements in lock structures, and more particularly to encasing means for a cylinder lock,—one object 15 of the invention being to provide a shell construction which may be readily adapted to doors of different thickness and which shall be provided with a simple and efficient ring construction at one end to seat against 20 the outer face of a door and also afford a recessed seat for the outer end portion of the casing of a cylinder lock located within said shell.

With this and other objects in view, the 25 invention consists in certain novel features of construction and combinations of parts as hereinafter set forth and pointed out in the claims.

In the accompanying drawings:

30 Figure 1 is a view in elevation of a shell structure embodying my improvements.

Figure 2 is a longitudinal sectional view showing a cylinder lock (in elevation) within the shell,

35 Figure 3 is an end view of the structure shown in Figure 2, and

Figure 4 is a sectional view showing a modification.

In the drawings, my improved lock enclosing shell is represented at 1, and a cylinder lock contained within the shell, is indicated at 2. The shell 1 is intended to pass through a bore in a door to enclose the cylinder and the latter may be secured to the 40 plate of a rim latch casing secured to the inner side of the door in any suitable manner, while the connecting bar 3 will be caused to cooperate with the latch mechanism in a manner well understood.

45 If desired, the enclosing shell may be made of hardened metal so that it will provide an efficient armor for the cylinder lock.

50 In order that the shell may be made adaptable for use in doors of different thickness, said shell is made adjustable by the

provision of a plurality of sections 4,—one or more of which may be removed to afford adjustment in the length of the shell.

To form the removable shell sections, said shell is provided with a plurality of series 60 of elongated slots 5, between adjacent ends of some of which, perforations 6 are made, and the metal of the shell is grooved as at 7, between adjacent ends of some of the slots and between the perforations 6 and the adjacent slot ends. In this manner, the inner portions of the shell are so weakened that the normally integral ring sections are so formed that one or more of them may be broken off to adjust the length of the shell 65 to accommodate said shell to the thickness of the door to which it is to be applied.

The outer end of the shell is provided with a head forming a facing ring 8. In the embodiment of the invention shown in 75 Figure 2, said head or facing ring is made as an integral part of the shell and comprises an annular flange 9 projecting laterally from the end of the shell; a beveled portion 10 (which may be slightly curved transversely if desired) projecting from the flange 9 and beyond the end of the shell, and a circular flange 11 which projects inwardly to the annular flange 9 and receives the head 12 of the cylinder lock 2,—the latter having 80 a seat on the inner portion of the flange 9. In this manner, the end of the shell is made with a facing ring which affords a recessed seat for the head of the cylinder lock 2.

In the embodiment of the invention 90 shown in Figure 4, the outer end of the shell is provided with a circumferential flange 13 forming an annular head on the shell and the inner face of the flange or head is recessed as at 14. A facing ring 15 to engage 95 the outer face of the door encircles the head or flange 13 and is formed with an inwardly projecting flange 16 seated in the recess 14, and preferably permanently secured to the facing ring by brazing, welding or soldering or in any other suitable manner. The inner edge portion of the facing ring 15 which projects beyond the head of the shell, is made with an annular flange 17,—the 100 inner edge of which may engage the head of the shell in such position that a portion of said head shall form a seat 18 for the head of the cylinder lock structure 2.

105 It will be seen that with my improvements, the facing ring structure constitutes 110

a fixed part of the shell providing a recessed seat for the head of the cylinder lock structure and that when the latter is secured to the casing of a rim latch, both the lock and the enclosing shell will be firmly secured to the door.

Slight changes might be made in the details of construction of my invention without departing from the spirit of the latter or limiting its scope, and hence I do not wish to restrict myself to the precise details herein set forth.

Having fully described my invention what I claim as new and desire to secure by Letters Patent, is:

1. A shell for a cylinder lock structure, having weakened portions providing a normally integral removable section, whereby adjustment of the length of the shell may be effected.

2. A shell for a cylinder lock structure, provided with a series of openings in its wall and having grooves between said openings, forming a normally integral removable shell section.

3. A shell for a cylinder lock structure, provided with a plurality of series of openings, each series of openings including elongated slots and perforations, said shell

having grooves between the openings of each series, the plurality of series of openings and grooves forming normally integral removable shell sections.

4. A shell for a cylinder lock structure, said shell provided at its outer end with an annular flange, a facing ring rigid with and projecting forwardly from said flange, said facing ring having an inwardly projecting part cooperating with the flanged end of the shell to provide a recessed seat for the head of a cylinder lock structure.

5. A shell for a cylinder lock structure, said shell provided at its outer end with a head, a facing ring having a flange engaging the peripheral portion of said head, said ring projecting beyond the head of the shell and having an annular flange concentric with the axis of the shell and cooperating with the head of the shell to form a recessed seat for the head of the cylinder lock structure.

In testimony whereof, I have signed this specification in the presence of two subscribing witnesses.

JOHN B. FREYSINGER.

Witnesses:

CHARLES A. BERRY,
JAMES L. INGALLS.
